(57) CLAIM

The ornamental design for a flag football jersey, as shown and described.

DESCRIPTION

FIG. 1 is a front view of a flag football jersey showing our new design;

FIG. 2 is a back view thereof;

FIG. 3 is a left side view thereof;

FIG. 4 is a right side view thereof;

FIG. 5 is a top view thereof; and,

FIG. 6 is a bottom view thereof.

The broken lines, shown throughout the views, represent the portions of the design which form no part of the claim.
